UNITED STATES PATENT OFFICE.

ENRICO GARDA, OF PARIS, FRANCE.

AUTOMATIC TABULATOR.

Application filed October 24, 1923, Serial No. 670,618, and in France November 4, 1922.

This invention relates to a monotype composing machine, which perforates a strip for controlling a casting machine.

This device is adapted to allow of effecting compositions divided in columns, by ensuring the automatic justification in each column or section.

It is essentially characterized by a drum carrying parallel screws on which are arranged adjustable nuts forming abutments for the external rack of the machine to which is adapted a hook which comes in engagement with these abutments. This drum automatically moves forward to the extent of a division each time one passes from a section to the adjacent section and that a line transfer key is acted upon, this operation sending compressed air to a piston controlling a driving pawl which acts on a ratchet rigid with the drum. This ratchet is also rigid with an index which moves with it and encounters a small bar to which is given a variable position on a disc graduated according to the number of columns. At the end of the line, the index engages with the small bar, causes the disc to rotate and with it a distributor which sends air under a piston releasing the retaining pawl of the drum and permitting the return to zero of the latter and controlling also the return of the racks.

The invention is illustrated, but by way of example only, in the accompanying drawing in which:

Figs. 1 and 2 are two diagrammatic views completing each other, showing the whole of the new device.

Fig. 3 is an elevation of the right hand end of the device as constructed.

Fig. 3^a is a similar view of the left hand end of the device.

Fig. 4 is a plan view of the right hand end of the device. Figure 4^a is a similar view of the left hand end of the device.

Figs. 5 and 6 are end views of the device.

Figs. 7 and 8 are two sections made respectively through lines A—A and A—B of Fig. 4.

Figs. 9, 10 and 11 are detail views.

As shown in the drawing, the new device comprises a drum 1, Fig. 1, composed of two plates 2, 3 between which are arranged parallel screws 4 carrying nuts 5 acting as abutments. These nuts are of special arrangement, as shown in Figs. 9 to 11; each of them is provided with a cap 6 jointed at 7; the

interior of this cap is screw threaded in such manner that, when the cap is turned down, it comes in engagement with the threads of the screws and that, when it is raised, the nut is released. It can be held closed by a socket 8 externally milled and internally threaded, screwing on a threaded bearing 5^a forming the end of the nut and fitting on conical portions of the nut and of its cap. The ends of the screws 4 fitted in the plate 3, project on the other side and are each provided with a slot in which can be engaged a screw driver 9, Fig. 3, having a milled head 10 and a returning spring 11. It results from this arrangement that for securing an abutment at the exact desired place, the socket 8 is loosened until the cap 6 is released; the latter is lifted and the nut 5 is rapidly moved along the screw 4. Then the socket 8 is moved and screwed. The screw-driver 9 is then pressed upon for bringing its end in contact with the head of the screw 4 and cause the latter to turn according to the necessary extent for completing the adjustment of the position of the nut 5.

A hook 12 comes in contact with the abutment 5; this hook is mounted on the outer rack 13 on which it is pivoted; a spring presses it against the screws 4 of the drum 1.

The plate 3 carries on its periphery a ratchet 14 which is in engagement with a driving pawl 15 and a retaining pawl 16. The pawl 15 can be actuated by the rod 17 of a piston 18 or by hand by means of a milled head 19. It can be released by a cam 20 actuated by the rod 21 of a piston 22, or by a milled head 23 actuated by hand.

On the shaft of the ratchet 14 is rigidly mounted a bevel pinion 24 gearing on another pinion 25 on the axis of which is rigidly mounted an index 26. The latter moves in front of a disc 27, loosely mounted on the axis, which comprises twelve sectors limited by notches 28. A small bar 29 can be inserted in any of these notches. For that purpose, it is rigid with a sleeve 29^a, capable of sliding on the axis of the pinion 26 and pushed by a spring against the disc.

The outer rack 13 is moved in the known manner by a pinion 30 rigid with another pinion 31 gearing with the inner rack 32 rigid with pistons 33, 34 movable in cylinders 35, 36.

The plate 27 carries on a portion of its periphery gear teeth 37 gearing with corresponding teeth 38 of a distributor 39 the

stroke of which is limited by a gudgeon 40, Fig. 2. This distributor is provided with a duct 41 which can put in communication the two cylinders 42, 43 wherein move the pistons 18 and 22.

The cylinder 42 communicates with an automatic valve 44 in relation with a two-way cock 45 which, in its turn, is in relation with a valve 46 adapted to cut off the air to the cylinder 36.

The operation is as follows:

Suppose a page is to be composed which is to comprise a number of sections or columns each having a determined width.

15 The small bar 29 is inserted in the notch 28 which follows the numeral appearing on the disc 27 and indicating the number of sections to be comprised in the page or table to be composed.

20 The position of each abutment 5 is adjusted on the corresponding screw. For that purpose, each screw is successively brought opposite the screw-driver 9; in order to effect this operation, the ratchet

25 14 is caused to rotate by hand by acting on the milled head 19 of the driving pawl. The adjustment of each abutment is first roughly effected by opening the cap 6 of the nut; then the adjustment of the position of the abutment nut is terminated by causing the screw which carries it to rotate.

When this adjustment is effected, the rack 13 is brought to zero by depressing any of the keys of the machine. At each depression,

30 the rack 13 advances to given extents according to the keys actuated by the action of an escapement mechanism diagrammatically illustrated at 47. This mechanism is that of the "monotype" machine; it is not modified and will not be described.

35 The two-way cock 45 which performs the office of distributor is opened by putting it in the position illustrated. Then the green transfer key is pressed upon or one of the lower red keys of the keyboard is depressed (one of these keys being diagrammatically shown at 48, Fig. 2); the return to zero mechanism operates as will be explained hereafter and the apparatus is ready.

40 The composition can then be begun by forming in each section the fraction of line the whole of which constitutes the line of the page or table.

45 By depression of the keys of the keyboard, the rack 13 progresses towards the zero of the scale E, Fig. 1. When the digit 4 of the scale (called the "ems" scale) is reached, a bell warns the operator that he approaches the end of the line (in the first section) and

50 that it is time to cut the word or to justify. At this moment, the drum 49 indicates, in the usual manner on the "monotype," two digits and it suffices to act on the key corresponding to these digits for automatically obtaining the justification.

One of the red keys of the lower row of the keyboard or the green key is then depressed, one of the keys being indicated at 48, as above stated.

By depressing this key, a passage is 70 opened for the compressed air in the cylinder 35, this air then acting on the piston 18. The latter actuates the pawl 15 and the ratchet 14 rotates to the extent of a tooth. The pawl 16 is withdrawn for allowing the 75 ratchet to rotate and then takes back its position in which it immobilizes the ratchet.

The piston 18 moving in the cylinder 42, uncovers an orifice 50, so that the compressed air passing through the valve 44 and the 80 distributor 45 passes along a pipe 51, acts in the cylinder 36 and pushes back towards the right the piston 34 and the inner rack 32. The outer rack comes back towards the left until it is stopped by the engagement of 85 the hook 12 with the new abutment 5 which, through the rotation of the drum having thus taken place, has replaced the preceding abutment.

The composition of the fraction of line 90 of the second section is immediately begun. The same operations as above are repeated and are subsequently repeated for all the sections up to the last one, that of the right hand.

95 The latter being composed, the index 26 owing to the successive advances of the ratchet to which it is connected by the pinions 24 and 25, has come in contact with the small bar 29; this small bar fitted in a notch 100 of the dial is integral with the same.

Thus, the following rotation of the drum, at the end of the line constituted by the whole of the fractions of line of each column, has for effect to drive with the ratchet 14 and the index 26, the small bar 29 and the disc 27.

105 The gears 37, 38 then rotate the distributor 39 the opening 41 of which causes the two orifices 42^a and 43^a to communicate. The compressed air then enters in the cylinder 43, behind, the piston 22. It enters also in the branch pipe 52 leading the air under the valves 44 and 46 one of which cuts off the exit of the air from the cylinder 42 115 and the other the admission of the air to the cylinder 36, this air coming from the cylinder 53 wherein moves a piston 54 actuating the drum 49 under the action of a spring or of a counterweight.

120 The piston 22 moving in the cylinder 43, actuates the cam 20; the latter acts on a boss 20^a of the fixed pawl, thus releasing the drum 1. This drum, under the action of a returning spring, such as a barrel 125 spring, indicated at 1^a (Fig. 1) comes back to its starting position.

130 This position is determined by an abutment 59. For allowing the drum to effect a complete revolution, this abutment moves

in a helical groove 60 which is illustrated in Figs. 3 and 4.

The index 26 moves backward and comes in engagement with a gudgeon 55 (Fig. 3) which is fixed on the dial 27; this index actuates the said dial as well as the distributor 39, this cutting off the admission of compressed air to the cylinder 43 and to the branch pipe 52.

10 The valve 44 is released and comes back, under the action of its returning spring, to the position illustrated; the air contained in the cylinder 42 escapes by passing through the distributor 45 and enters in the cylinder 36 in which it actuates the piston 34 which brings back the rack to the starting point.

The same actions are repeated upon composition of the following line and so on.

20 From the foregoing it will be seen that the new device comprises a mechanism of advance section by section and a mechanism for the automatic return to the first section, which do not require any operation during 25 the work and, consequently, do not necessitate any attention on the part of the operator.

During the rotation of the abutment-carrying drum coming back to its initial position, the rack does not move. It is only after the drum has come back to the starting point that the rack moves and that its hook 12 comes in engagement with the first abutment. It results therefrom that this 35 abutment can be, without inconvenience, very near the ratchet 14. This would not be the case if the above movements were simultaneous. In case the first section would be very narrow, the drum would not have time 40 to effect its return before the hook is in position for engaging its abutment.

The new device has moreover, the main following advantages:

1.—It is possible, at any moment, to interrupt the tabular composition and to effect, for instance in case of urgency, the composition of an ordinary text on any desired justification, without having to modify the adjustments of the automatic tabulator; 50 the only operation to be effected for passing from the tabular composition to the ordinary composition, consists in turning in the suitable direction the two-way cock 45.

2.—The justifications of the various 55 columns can differ only of a length as small as desired, a single unit (1/18 of a quadrate) for instance, and this adjustment is ensured by means of a nut which can be moved at any moment to the necessary extent.

3.—In addition to the pneumatic control, automatically causing, the various justifications to succeed each other in the predetermined sequence, it is possible, at any moment, to bring back the tabulator by hand

to any of the justifications provided; when several columns of a table have the same justification, it suffices therefore to adjust according to this justification only one of the adjustable abutments of the tabulator; 70 thus in the case of a work of small importance, the loss of time caused by several identical adjustments is avoided and, moreover, the abutments not used for other justifications are available, so that the number of 75 the columns of a table can thus be very high.

4.—The independence of the pneumatic control and of the direct control by hand allows of instantaneously bringing back the tabulator to zero (starting point of a line) 80 in case of an error noticed in the composition of the line being composed.

5.—The indication of the number of the column of which the tabulator ensures the automatic justification is constantly in sight 85 of the operator in normal working position.

6.—The warning bell indicating the end of the line and provided on the keyboard of the machine on which is fitted the tabulator, operates for each of the sections of 90 line corresponding to a column of the table.

Moreover, the justification drum which indicates, at the end of each line, the total length, of blanks which is to be distributed and the number of variable spaces between 95 which it must be distributed, automatically operates in proper time for each of the sections of the line.

7.—The tabulator allows the justification of lines having a length inferior to 4 ems (or four quadrates), lower limit of justification of the machine not provided with the tabulator, provided the whole of the section of one and the same line comprises at least the seven letters, signs or spaces necessary for casting machine for sending to the galley the composed line. That is to say, by means of the tabulator, shorter lines can be made than heretofore.

The above arrangements are, of course, given by way of example only; the forms, dimensions, materials used and all detail arrangements may be varied according to circumstances without departing thereby from the principle of the invention.

Claims:

1. An automatic tabulator for monotype machines having a drum formed by parallel screws, abutments forming nuts mounted on the screws, an external rack, a hook on the external rack cooperating with these abutments, and means for advancing the drum at each section of the line.

2. An automatic tabulator for monotype machines having a drum formed by parallel screws, abutments forming nuts mounted on the screws, an external rack, a hook on the external rack cooperating with these abutments, means for advancing the drum at each section of the line, and means for auto-

matically releasing the drum at the end of the line.

3. An automatic tabulator for monotype machines having a drum formed by parallel screws, abutments forming nuts on the screws, an external rack, a hook on the external rack cooperating with these abutments, means for advancing the drum at each section of the line, and means for automatically releasing the drum at the end of the line and to return it to zero.

4. An automatic tabulator for monotype machines having a drum formed by parallel screws, abutments forming nuts mounted on the screws, an external rack, a hook on the external rack cooperating with these abutments, a ratchet forming one piece with the drum, a pawl for advancing and engaging with the ratchet moved pneumatically when the return key is pressed, which key exists already on the machine.

5. An automatic tabulator for monotype machines having a drum formed by parallel screws, abutments forming nuts mounted on the screws, an external rack, a hook on the external rack cooperating with these abutments, a ratchet forming one piece with the drum, a pawl for advancement engaging with this ratchet, a distributor actuated by the drum at the end of the line, and means for releasing the drum by this distributor.

6. An automatic tabulator for monotype machines having a drum formed by parallel screws, abutments forming nuts mounted on the screws, an external rack, a hook on the external rack cooperating with these abutments, a ratchet forming one piece with the

drum, a pin on this ratchet, a bar cooperating with this pin, a graduated disc forming one piece with this bar, and a distributor releasing the drum.

7. An automatic tabulator for monotype machines having a drum formed by parallel screws, abutments forming nuts mounted on the screws, an external rack, a hook on the external rack cooperating with these abutments, a ratchet forming one piece with the drum, a pawl for advancing engaging with this ratchet moved pneumatically with the return key when pressed, which key exists already on the machine.

8. An automatic tabulator for monotype machines having a drum formed by parallel screws, abutments forming nuts mounted on the screws, an external rack, a hook on the external rack cooperating with these abutments, a ratchet forming one piece with the drum, a pawl for advancing engaging with this ratchet moved pneumatically when the return key is pressed, which key exists already on the machine, and means for pneumatically actuating these pawls.

9. An automatic tabulator for monotype machines having a drum formed by parallel screws, abutments forming nuts mounted on the screws, an external rack, a hook on the external rack cooperating with these abutments, means for advancing this drum at each section of the line, a cock with a plurality of wheels placing the parts in action when desired.

The foregoing specification of my "automatic tabulator" signed by me this 10th day of October 1923.

ENRICO GARDA.
